his Attorney.

UNITED STATES PATENT OFFICE

2,165,142

SAFETY SHIELD

Charles R. Jeffreys, McKeesport, Pa.

Application November 17, 1937, Serial No. 175,131

1 Claim. (Cl. 51—272)

This invention relates to safety shields, and more particularly to one which is adapted for use on a grinding-wheel or similar device, although not limited thereto.

In using grinding-wheels and the like, considerable danger to the operator is occasioned by flying sparks, metal, and abrasive particles. A number of devices have been proposed for eliminating this hazard but are characterized by a number of disadvantages, such as expense, lack of complete protection from all working angles, etc.

It is among the objects of the present invention to provide a novel safety shield which is inexpensive to produce and install on apparatus of existing design, and one which affords complete protection to the workman from all possible working angles.

The foregoing and other objects will be apparent after referring to the drawing in which:

Figure 1 is an end elevation of the device of the invention as applied to a rotary grinding-wheel, and illustrates in dotted lines a number of positions it may occupy.

Figure 2 is a perspective.

Figure 3 is a sectional view on the line III—III of Figure 1.

Referring more particularly to the drawing, the numeral 2 designates a prime mover having a driving-shaft 3 on which there is mounted a conventional rotary grinding-wheel 4. A suitably mounted band 5 is disposed to extend for a limited distance around the upper portion of the periphery of the rotary grinding-wheel 4. This band 5 carries a stud 6 which is held against rotation by means of a nut 7. The stud 6 carries a clamp 9 having a cylindrical aperture 10 formed between a pair of legs 12 which are adjusted with respect to each other by means of a conventional clamping-screw 14. An elongated shaft 15 is disposed to extend through the cylindrical aperture 10 in the clamp 9 and is made relatively adjustable with respect thereto, due to the operation of the clamping-screw 14. The elongated shaft 15 is of such length as to enable one of its ends to project outwardly from the adjacent portions of the rotary grinding-wheel 4 and the banding 5. This end of the elongated shaft 15 is provided with a transverse aperture 17. The

elongated shaft 15 carries a slidable clamping-block 18 having a semi-cylindrical recess 19 which conforms to a portion of the contour of the transverse aperture 17. The carrier-rod 20 of the shield per se is disposed to extend through the transverse aperture 17 in the elongated shaft 15 and the slidable clamping-block 18 is held tightly against it by means of a nut 22 which is threaded onto the shaft 15.

The shield per se is shown as comprising a rectangular wire loop 25 having a flat central-portion 26 and a pair of divergent end-portions 27 which are directed toward the grinding-wheel 4. The carrier-rod 20 of the shield comprises a central-portion 29 which extends through the transverse aperture 17 in the elongated shaft 15 and a pair of right-angular leg portions 30. These leg portions 30 cross and are welded to the ends of the flat central-portion 26 of the shield, thus making three sections of the latter which are provided with safety glass.

While I have shown one specific embodiment of the present invention, it will be seen that I do not wish to be limited exactly thereto, since various modifications may be made without departing from the scope of the invention as defined by the following claim.

I claim:

A safety shield for abrading or cutting tools and the like comprising a wire U-shaped member having its leg portions extending toward the station of the operator, a wire elongated loop member, said wire elongated loop member having a central substantially flat portion which is welded to and extends across the leg portions of said wire U-shaped member, the ends of said wire elongated loop member being extended out of the plane of said substantially flat central portion and toward the work, transparent window material disposed in and framed by the flat central portion and the extended end portions of said wire elongated loop member, and a rod disposed over the work and extending toward the station of the operator, said rod being connected to the base portion of said wire U-shaped member and constructed and arranged to permit the rotative adjustment of the latter.

CHARLES R. JEFFREYS.
